United States Patent Office

Des. 222,333

Patented Oct. 19, 1971

222,333

PITON

William A. Feuerer, 2009½ Oak St.,
Santa Monica, Calif. 90405

Filed Apr. 23, 1970, Ser. No. 22,579

Term of patent 14 years

Int. Cl. D8—08

U.S. Cl. D8—230

Fig. 1

Fig. 3

Fig. 2

Fig. 4

Fig. 5

FIG. 1 is a perspective view of the top and one side of a piton showing my new design;

FIG. 2 is a side elevational view of the other side;

FIG. 3 is an end elevational view, taken of the right end in FIG. 1;

FIG. 4 is an end elevational view taken of the right end in FIG. 2; and

FIG. 5 is a bottom plan view.

I claim:

The ornamental design for a piton, substantially as shown.
